Attorney.

UNITED STATES PATENT OFFICE.

ERNST BRAUCHLI, OF ST. GALLEN, SWITZERLAND.

BOOK-HOLDER.

1,385,663.

Specification of Letters Patent. Patented July 26, 1921.

Application filed April 13, 1921. Serial No. 461,133.

To all whom it may concern:

Be it known that I, ERNST BRAUCHLI, a citizen of the Swiss Confederation, residing at St. Gallen, Switzerland, have invented 5 certain new and useful Improvements in Book-Holders, of which the following is a specification.

The present invention has reference to certain new and useful improvements in 10 book holders, and it relates more particularly to a construction of book holder which can readily be adjusted to different angular position relative to the reader's face, so that it will hold the book substantially parallel 15 to the reader's face with the reader in sitting-up or more or less recumbent position.

In order to make my invention more readily understood, I will now describe it in detail in connection with the accompanying drawing, in which Figure 1 is a front view of the holder; Fig. 2 is a fragmental section on line A—A, and Fig. 3 a section on line B—B of Fig. 1; Fig. 4 is a top view of the device, partly in section, and Fig. 5 shows the book holder in connection with a 20 floor stand supporting also a tray for smoking utensils or the like and a reading lamp.

The main carrier bar presents lateral 25 guide arms 4 of U-shaped cross-section and intermediate thereof a cylindrical enlargement 5; a clamp 1 surrounds this middle portion 5, the laterally extending clamp arms 15 being alinedly perforated to receive the tightening bolt 3 with wing nut 35 17. The bolt 3 is fixed on the socket member 2. The double frame 6, of upstanding front and rear loops, the two rear ones of 40 which are connected by a slightly curved bridge piece 7, is rigidly supported on the carrier bar.

Two flat arms 8, terminating outwardly in eyes 16, are slidably arranged within the carrier bar and are provided with stops 9 (Fig. 4) to limit their relative displacement 45 to the extent of the length of the enlargement 5. In the eyes 16 engage the lower ends of the bent-off leaf holders 10. The holder P (Fig. 5) is secured by the socket 2 to one end of an elbow support 11, whose 50 other ends is suitably secured to a floor stand 12, which also carries a small table 13 and a reading lamp 14.

For inserting a book, first the arms 8 are drawn out of their guiding arms 4, the opened-up book is then inserted with the 55 cover boards in between the respective pairs of front and rear loops of the frame 6, and lastly the leaf holders 10 are swung into position in contact with the unprinted outer margins of the book pages, the arms 8 being 60 simultaneously shoved home in their guide arms to the required extent depending upon the width of the pages. The wing nut 17 is now eased, the entire holder P with the 65 clamped book is tilted into the desired angular position and the clamp 1 is then tightened again on the cylindrical portion 5 of the carrier bar by manipulation of the wing nut 17.

By dispensing with the floor stand, provision may be made to clamp the support 11 or the clamping member 1 directly onto a chair, bedframe, or other piece of furniture.

What I claim is:

1. In a device of the character stated, a 75 carrier bar, presenting a cylindrical middle portion and laterally extending guide arms of U-shaped cross-section, a double frame upstandingly fixed to said carrier bar and comprising two pairs of front and rear 80 loops, a bridge piece connecting the two rear loops, arms slidably arranged in said guide arms, eyes forming the outer extremities of said slide arms, stop means associated with said slide arms, leaf holders swingingly 85 supported in said slide arm eyes, and clamping means for releasably securing said assemblage of parts to a fixed object.

2. In a device of the character set forth, a 90 carrier bar presenting a cylindrical middle portion and laterally extending guide arms, a double frame upstandingly fixed to said carrier bar and comprising two pairs of front and rear loops, adapted to receive between them the opened-up cover boards of 95 a book, a bridge piece connecting the two rear loops, arms slidably arranged in said guide arms and eyes at the extremities of said slide arms, stop means on said slide arms designed for coöperation with said 100 cylindrical carrier bar portion to limit the relative longitudinal displacement of said slide arms, bent-off leaf holders supported in said slide arm eyes, and clamping means,

comprising a slit tubular member snugly surrounding said cylindrical carrier bar portion, two apertured arms respectively laterally extending from the slit edges of 5 said tubular member, a member adapted to be adjustably secured to a fixed object, and

screw bolt and nut means coöperating with said apertured arms and said screw bolt in fixed connection with said adjustably securable member.

In testimony whereof I affix my signature.

ERNST BRAUCHLI.
